UNITED STATES PATENT OFFICE.

WILLIAM LEIGH, OF PITTSBURG, PENNSYLVANIA, ASSIGNOR OF ONE-HALF
TO WICKLIFFE C. LYNE, OF WILKINSBURG, PENNSYLVANIA.

CALENDAR.

SPECIFICATION forming part of Letters Patent No. 669,959, dated March 12, 1901.

Application filed October 23, 1900. Serial No. 34,013. (No model.)

To all whom it may concern:

Be it known that I, WILLIAM LEIGH, a citizen of the Untied States of America, and a resident of Pittsburg, county of Allegheny, 5 State of Pennsylvania, have invented certain new and useful Improvements in Calendars, of which the following is a specification, reference being had to the accompanying drawings, forming a part of this specification, in 10 which—

Figure 1 is a perspective view of a block-leaf calendar provided with interspersed bound-in mailing devices. Fig. 2 is a similar view showing the calendar-leaf raised, exposing one of such devices. Fig. 3 is a side view of the calendar.

My invention relates to calendars, and has particular reference to the incorporation with a calendar of devices—such as envelops, postal cards, &c.—in such a manner that at intervals of time, represented by the frequency of their insertion, such devices will be exposed and appear in the usual progress of using the calendars, as from day to day. When so exposed, the device is adapted to be removed and sent by the user in the manner usual with such mail-matter.

Referring to the drawings, 2 represents the ordinary leaves of a calendar, which in one 30 of the commonest forms are bound together with perforations 3 to facilitate tearing. At intervals of time—several days or weeks, as indicated by the calendar-leaves, or of whatever length of time may be desirable, according to the use to which the invention is to be put—mailing devices, such as postal cards 4 or envelops, are bound between the leaves, and also perforated or bound in such manner to facilitate tearing. This may be done by 40 binding a very narrow edge of the card, as indicated in the drawings. The mailing devices may be already addressed and stamped and provided with any advertising matter, information having particular relation to any 45 particular time of year with relation to certain goods or business, or generally, or they may be provided with any appropriate or suitable inscription or legend or blank for writing signatures, &c., within a wide range and variety.

50 Particular adaptations of the invention may be made by parties using it for their particular

purpose, and such use will be readily understood and appreciated.

The advantage of my invention over the ordinary printed advertising-slips are considerable, as by inserting an already addressed and stamped mailing device the inducement to insert the name of the sender and then mail is increased and the trouble of the operation reduced to a minimum, inasmuch as it 55 is necessary to tear the mailing devices in any event in order to continue using the calendar. In fact, the inclination to use a stamped device will be greater than the inclination to discard it, and in this respect my 60 invention will be found superior for the purpose in view to other advertising-calendars.

The mailing devices may be employed with any calendar wherein the leaves are periodically removed either daily or at longer intervals, the object in view being to so incorporate the devices with the calendar that they will come into view at certain predetermined periods throughout the year or any portion of it.

Having described my invention, what I claim is—

1. In combination with a calendar; an addressed and stamped mailing device detachably incorporated with it in such a manner 80 as to become exposed in the course of using the calendar and to be removed in the manner of removing the calendar-leaves, substantially as set forth.

2. In combination with a calendar comprising a series of indicating-leaves detachably bound together in the regular order of time, separate addressed and stamped mailing devices detachably bound in with the leaves, so that such devices will be exposed and must 90 be removed to expose the next calendar-leaf, substantially as set forth.

3. In combination with a block-calendar comprising a number of perforated sheets permanently bound together on one side of 95 the perforations and adapted to have their other parts torn off in consecutive order, of a number of perforated mailing devices interspersed between the sheets and bound on one side of their perforations with the bound 100 ends of the sheets whereby said mailing devices are compelled to be torn away at inter-

vals in order that the calendar may continue to be used in the manner for which it is designed.

4. In combination with a calendar comprising a number of sheets bound together in a block, each sheet representing a period of time and adapted to be torn from the binding at the end of that time, of a number of mailing devices interspersed between the 10 sheets and bound to the calendar-binding,

said mailing devices being necessarily removed at intervals for the continued use of the calendar in the manner for which it is designed.

Signed at Pittsburg, Pennsylvania, this 1st 15 day of October, 1900.

WILLIAM LEIGH.
